Fig. 1.

Fig. 2.

Fig. 3.

Fig. 4.

Fig. 5.

Fig. 6.

FIG. 1 is a top plan view of a combined battery cable cutting tool and wire stripper showing our new design;

FIG. 2 is an elevational view of one side thereof;

FIG. 3 is an elevational view of one end thereof;

FIG. 4 is a top plan view of another embodiment of our new design;

FIG. 5 is an elevational view of one side thereof; and

FIG. 6 is an elevational view of one end thereof.

The appearance of the respective embodiments in bottom plan, and the appearance of the sides and ends opposite those shown in FIGS. 2, 3, 5 and 6 are apparent from the views shown.

I claim:

The ornamental design for a combined battery cable cutting tool and wire stripper, substantially as shown and described.
